UNITED STATES PATENT OFFICE.

WILLIAM E. DIPPERT, OF DES MOINES, IOWA.

DESIGN FOR A TRACE-CARRIER.

SPECIFICATION forming part of Design No. 33,382, dated October 16, 1900.

Application filed May 12, 1900. Serial No. 16,527. Term of patent 14 years.

To all whom it may concern:

Be it known that I, WILLIAM E. DIPPERT, a citizen of the United States of America, and a resident of Des Moines, Polk county, Iowa, 5 have invented a certain new and original Design for a Trace-Carrier, of which the following is a specification.

The object of this invention is to provide a new and original design for a trace-carrier.

10 My invention consists of the design herein-after set forth, pointed out in my claim, and illustrated by the accompanying drawings, in which—

15 Figure 1 is a perspective of a complete device, illustrating my design. Fig. 2 is a transverse section of a trace-carrier embodying my design.

In the design as shown the numeral 10 designates a ring approximately circular in plan

and having an arch 11 diametrically thereof. 20 A loop or eye 12 projects radially from the ring 10 adjacent one end of the arch 11, and a loop or eye 13 projects from the ring 10 adjacent the opposite end of said arch. Arms 14 15 project laterally in opposite directions 25 from the central portion of the arch 11, and said arms are curved downwardly at their central portions and extend into the space bounded and inclosed by the ring 10.

I claim as my invention—

30 The design for a trace-carrier, substantially as herein shown and described.

Signed by me at Des Moines, Iowa, this 27th day of January, 1900.

WILLIAM E. DIPPERT.
